UNITED STATES PATENT OFFICE

HARRY J. ROBINSON, OF BOSTON, MASSACHUSETTS, ASSIGNOR TO THE MOSLER SAFE COMPANY, OF HAMILTON, OHIO, A CORPORATION OF NEW YORK

NIGHT SAFE DEPOSITORY

Application filed May 25, 1928. Serial No. 280,470.

This invention relates generally to a night safe depository and more particularly to a safe arrangement for banks whereby money and valuables may be dropped into a chute and conducted to a burglar and fire proof vault for safe keeping after banking hours.

Business men generally keep their stores and establishments open for trade long after the particular bank or trust company with which they do business is closed. After the day's sales or business transactions are over, the business man is confronted with the problem of protecting the cash, notes or valuables taken in, from the hazards of stealth or fire. The size of his business may not warrant the installation of safe apparatus necessary to properly protect his property. A distinct need therefore arises for some suitable depositing facility for the business man conducting business after banking hours.

An object of my invention is to provide a depositing facility especially adapted to be installed in banks which will hold in safe-keeping valuables deposited therein.

Another object of this invention is to provide a night safe depository with an article receiving passage having means to permit article insertions into the passage but preventing article removals therefrom.

Another object of this invention is to provide a night safe depository having mechanism operative to indicate when the article deposited in the conducting passage thereof has passed safely into the storage vault.

Another object of this invention is to provide a shutter device which will open an amount sufficiently only to permit the article deposited to pass and then signal such passing to the depositor.

Another object of this invention is to provide a night safe depository having a plurality of safety devices operating separately.

Another object of my invention is to provide a night safe depository that will signal any unauthorized tampering therewith.

Another object of my invention is to provide a night safe depository strong, durable, pleasing in appearance and affording a high degree of protection against burglary and fire.

Further objects of my invention will become evident as the disclosure proceeds.

In order that a clearer understanding of this invention may be had, attention is hereby directed to the accompanying drawings forming a part of this application and illustrating certain possible embodiments of my invention.

Referring to the drawings, Fig. 1 is a vertical cross-sectional view of my night safe depository installed in a bank or other building.

Fig. 2 is a face view of the passage entrance structure with the door to the passage opened, and the covers removed from the signal light bulbs.

Fig. 3 is another face view of the passage entrance structure with the door to the passage closed.

Fig. 4 is a vertical cross-sectional view of the passage entrance structure, taken on line 4-4 of Fig. 3.

Fig. 5 is a vertical cross-sectional view of the portion of the article passage showing the baffle plates therein in enlarged outline.

Fig. 6 is a horizontal cross-sectional view of the same, and is taken on line 6-6 of Fig. 5.

Fig. 7 is a vertical cross-sectional view of the housing, and is taken on line 7-7 of Fig. 5.

Fig. 8 is a vertical cross-sectional view of a portion of the passage entrance structure showing a signal light bulb positioned therein, taken on line 8-8 of Fig. 3.

Fig. 9 is a wiring diagram of the signal device operated by the baffle plates.

Fig. 10 is a cross-sectional view showing a modified manner of locking the cover-plate to the housing; and

Fig. 11 is a sectional view thereof, taken on the line 11-11 of Fig. 10.

Similar reference characters refer to similar parts throughout the several views of the drawings.

Referring to Fig. 1, the article conducting passage of my night safe depository is shown installed in a wall 1 of a building and leads from a passage entrance on one side of the wall to a suitable storage vault 2 on the

other side thereof. The storage vault is shown positioned in the basement of the building, with the banking floor 3 thereabove. It is understood, however, that the 5 passage and vault positioned as shown in Fig. 1 is merely for the purpose of illustration and that the passage and its receiving vault may be positioned in a building, within the scope of this invention, in any 10 place or in any manner convenient and desirable.

The passage and its receiving vault are suitably encased in reinforced concrete 4 to afford the greatest protection against burglary, theft and the hazards of fire. The 15 receiving vault may be of the ordinary safe variety with an opening 5 at its top into which article conducting conduit 6 leads. Article conducting conduit 6 may be made 20 of sheet steel or iron castings and is preferably square in horizontal cross-section.

The passage entrance comprises an elbow extension 7 and an entrance structure 8. The elbow extension 7 connects the upper end of 25 conduit 6 to the entrance structure 8.

The body portion of the entrance structure may be integrally cast with an article entrance opening formed in the center and an elongated recess formed along the top, 30 bottom and one side thereof. The article entrance opening as shown in Figs. 2 and 3 is closed by a strong door 9 hinged at 10 to the body portion and provided with a suitable lock 11. The top recess 12 formed 35 in the body portion above the door is adapted to contain a pair of electric light bulbs suitably secured by means of brackets 14 therein. A pair of similar light bulbs 15 are secured with the bottom recess 16 below 40 the door by brackets 17. Lead wires 18, 19, 20 and 21 pass through a wire conduit 22 and connect the respective bulbs to a suitable power source to form a closed electric circuit. Thus it is seen that in operation the 45 bulbs in the top and bottom recesses burn constantly. Cover plates 23 carry suitable lettering illuminated by the light bulbs, to direct depositors. The cover plates are removably secured over the respective top and 50 bottom recesses by means of stud bolts 24 extending from the bottom of each recess and cooperating with screw caps 25 carried by the cover plates as shown in Fig. 8. Transparent lettering portions 26 may be used as 55 shown more particularly in Fig. 8. These lettering portions are secured to the cover plate by means of screws 27 passing through a backing plate 28 and the raised lettering portion, and into the cover plate.

60 The side recess 29 opposite the front edge of the door as shown in Fig. 4, likewise contains a pair of electric light bulbs 30 secured therein by means of suitable brackets 31. Lead wires 32 and 33 passing through wire 65 conduit 22 connect the respective bulbs to a

suitable power source, forming an electric circuit. Within this electric circuit is a plurality of switch devices operative to close and open the circuit. The purpose and operation of the switch devices will hereinafter be 70 described. Cover plate 34 is removably secured to the side recess by means of stud bolts 35 projecting from the bottom of the recess and adapted to cooperate with screw caps 36 carried by the cover plate 34. A transparent disk 37 of colored glass may be fitted within an aperture in the cover plate and held in place therein by means of screws 38 and a backing plate 39.

A flange 40 formed on the body of the entrance structure cooperates with flange 41 formed on the elbow extension to support the entrance structure in position.

Elbow extension 7 may be also provided with lug formations 42 through which screw bolts 43 are adapted to pass to secure the entrance structure thereto.

A V-shaped article receiving bucket 44 is positioned to pivot about its apex within the elbow extension 7 as shown in Figs. 1 and 2. 90 Roof portion 45 of the elbow extension is of such curvature that at least one wall of the bucket will keep the passage always completely closed. When the bucket is swung outwardly to its greatest extent, as shown in Fig. 1, the rear wall 46 completely closes the passage. When the bucket is swung rearwardly to its greatest extent, the front wall 47 closes the passage, as shown in dotted lines Fig. 1. Thus it is seen that no matter 95 in what position of swinging movement the bucket may be, the passage is always kept closed thereby and no implement or device can be inserted beyond the bucket into the article conducting passage. The bucket may 100 be provided with a suitable handle 48 for tilting the bucket forwardly or rearwardly.

Some distance below the bucket 44 a series 105 of baffle plates 49, horizontally aligned, are pivoted for swinging movement within the 110 passage. One end of each baffle plate is preferably positioned in a suitable housing 50, secured by means of bolts 51 to the side of the article conducting conduit 6, and project through an opening 52 in the conduit 115 as shown in Figs. 5 and 6. A rod 53 extending horizontally across the housing is fixed to the side walls thereof. Baffle plates 49 are journaled to rod 53 through weight blocks comprising clamping portions 54 and 55 between which the rod extends. A screw 56 may be used to secure each upper clamping portion 54 to its respective baffle plate and a clamping bolt 57 used to removably hold each lower clamping portion 55 in position. 120 Washers 58 positioned on the rod 53 may be used to hold the blocks and baffle plates in spaced relation. The weighted blocks overbalance the baffle plates and keep their outer extremities normally in abutting contact 125 130

with the opposite side wall of the article conducting conduit 6. It is thus seen that the conduit is normally kept closed and only opened by the weight of an article striking the baffle plates from above. They then pivot downward sufficiently to permit the article to slide through. Since the plates pivot about rod 53 independently, such a number of plates only will swing downwardly as necessary to permit the article dropped into the conduit to pass. Furthermore, as shown in Figs. 1 and 5, it is seen that articles are permitted to pass through the baffle plates in a downward direction only, any article or device striking the plates from underneath would only move the plates to passage closing position.

An electric switch device is positioned under each baffle plate weight within the casing. Each switch device is preferably mounted on a suitable block 59 secured within the casing and comprises an electric terminal 60 overlying terminal 61. The terminals are insulated from each other by suitable insulating material 62. Lower terminal 61 resiliently overhangs the block 59. The lower terminal is normally depressed and held out of electric contact with contact point 63 of the upper terminal 60 by the weight of the baffle plate blocks resting on contact block 64 carried on the end of the lower terminal.

Wires 32 and 33 leading from the light bulbs 30 are joined to a common conductor 65 which passes through wire conduit 22 heretofore described. Conductor 65 leads into the housing 50 and is connected to one of the terminals of each switch device. The other terminal of each switch device is connected to a wire 66 leading from the housing through electric conduit 67 to a suitable power source. It is thus seen that each switch device is connected in series arrangement with the light bulbs 30 in the article entrance structure. The closing of any switch in the series therefore functions to close the electric circuit and light the bulbs 30, as illustrated in Fig. 9. It is understood that a slight downward movement or disturbance of any of the baffle plates 49 projecting into the article conducting passage will tend to slightly relieve the weight from its corresponding switch terminal 63. This will permit the lower terminal 61 to spring into electrical contact with the upper terminal 60 of the switch device to close the electric circuit and light the bulbs. Since one or more plates are swung downwardly by an entering article, the passage of the article through the baffle plates will always be signalled by the lighting of the bulbs 30. Furthermore any unauthorized tampering with the baffle plates will be likewise signalled. The baffle plates are adapted to swing downwardly to such an extent as to parallel the walls of the passage

if the size of the entering article demands, as shown in dotted lines Fig. 5.

The enclosure of the switch devices and weighted ends of the baffle plates within the housing 50 prevents any unauthorized tampering therewith by means of devices inserted through the conducting passage. Electric conduit 22 may be secured at one end to the back of the article entrance structure, as shown in Fig. 4, and secured at its other end to an offset portion 68 of the housing, as shown in Figs. 6 and 7. A suitable cover plate 69 is removably secured to the housing 50 by means of bolts 70, permitting access to the housing from the inside of the building to adjust or repair the mechanism contained therein. The passage to the storage vault may be given one or more reverse curves if desired as added protection against the intrusion of burglar implements therethrough.

A preferred and modified construction for securing cover plate 69 to the housing is illustrated in Figs. 10 and 11. In this preferred construction, the cover plate can only be removed by first gaining access to the storage vault 2 through its door and unlocking the cover plate from the interior of the vault. To this end, I provide a U-shaped locking bar having a bottom cross bar 71 and side bars 72 and 73. A plurality of long bolts 74 (four being shown in the drawings) are preferably permanently secured to the cover plate 69 and are of such length as to extend through the housing 50. Each bolt is provided with an enlarged head 75 at its inner end. The inner end of each bolt projects through an elongated slot 76 in the side bar. Each slot 76 terminates in an enlarged opening 77 of such size as to permit the head 75 of the bolt projecting therethrough to slip through the enlarged opening when the U-bar has been moved to the proper position. A plurality of screws 78 extend through elongated slots 79 in the side bars 72 and 73 and into the wall of chute 6, securing the U-bar against removal but permitting a slight vertical sliding movement thereof. Guide members 80 in the form of metallic tubes secured within the housing may be provided to guide the bolts 74 into position. The outside plates 49 are spaced apart from the adjoining plates sufficiently to permit the side bars 72 and 73 to extend freely therebetween. Thickened washers 58 maintain the outside plates in proper spaced position.

As shown more clearly in Fig. 11, the U-bar projects into the interior of vault 2 a short distance. It is seen that by gaining access to the vault through its door the hand can be inserted into the vault and a lifting force exerted upon the U-bar. The U-bar is thus lifted until bolt heads 75 can be disengaged from their respective slots 76 and slipped through the enlarged openings 77. The cover plate can then be removed. Thus it

is understood that means have been provided by which cover plate 69 can only be removed by gaining access to the vault through the vault door and valuables cannot be removed from the vault by any unauthorized access thereto through the housing 50.

Preferably each depositor is provided with a key by means of which he may unlock outer door 9, although a combination lock may also 10 be used within the contemplation of this invention. Having opened the door 9, the depositor tilts the bucket 44 forwardly by means of its handle and places the bagged valuables or articles to be deposited therein. The 15 bucket is then tilted rearwardly, dumping the article into the conducting conduit 6, down which it slides and drops. When the article strikes the baffle plates 49 in its downward movement, bulbs 30 in the entrance 20 structure are illuminated. The article finally lodges safely within the storage vault 2. Even though outer door 9 is opened, bucket 44 prevents the entrance of burglar tools and 25 appliances into the passage and vault at all times. Both the bucket 44 and the baffle plates 49 prevent withdrawals through the passage. Furthermore, any passage of articles or tools into the passage will be signalled by bulbs 30, giving notice to anyone in the 30 vicinity that either deposits are being made or the apparatus is being tampered with in an unauthorized manner. Thus it is seen that a number of safety devices are incorporated in my depository, insuring the greatest protection to the valuables deposited.

As many changes could be made in the above arrangement, and as many apparently widely different embodiments of this invention could be made without departing from 40 the scope thereof, it is intended that all matter contained in the above description or shown in the accompanying drawings should be interpreted as illustrative and not in a limiting sense.

45 What I claim is:—

1. In combination with a deposit vault, an article conducting passage leading thereto, a series of baffle plates hinged for swinging movement in said passage, an opening in said 50 passage through which access can be had to adjust said baffle plate when necessary, a closure member for said opening, and means operative from the interior of the vault for locking said closure member in place to prevent unauthorized tampering with said baffle plates, said means including a stud projecting inwardly from said closure member, and 55 rack member vertically reciprocable from the interior of the vault to place the same into and out of engagement with said stud.

2. The combination with a deposit chute having a wall, a housing on the exterior of said wall, means mounted in said housing and extending into the chute permitting articles 60 to pass through the chute in one direction

only, a cover plate for the housing, and means, including a member extending from the cover plate into the chute and a coacting locking member mounted on the interior of said chute wall, whereby said cover plate is locked in 70 place on said housing.

3. The combination with a deposit chute having a wall, a housing on the exterior of said wall, means mounted in said housing and extending into the chute permitting articles 75 to pass through the chute in one direction only, a cover plate for the housing, and means, including recessed members secured to the cover plate and extending into the chute and locking members mounted on the interior of said chute wall and adapted to engage in the recesses of said recessed members, for locking said cover plate in place on said housing.

4. The combination with a deposit chute having a wall, a housing on the exterior of 80 said wall, means mounted in said housing and extending into the chute permitting articles to pass through the chute in one direction only, a cover plate for the housing, means, including a member extending from the cover plate into the chute and a coacting locking member mounted on the interior of said chute wall, whereby said cover plate is locked in 85 place on said housing, a depository into which the chute delivers articles passed therethrough, and means accessible only within the depository, whereby said coacting locking member may be adjusted to release said cover plate for removal from the housing.

5. The combination with a deposit chute having a wall, a housing on the exterior of said wall, means mounted in said housing and extending into the chute permitting articles to pass through the chute in one direction only, a cover plate for the housing, and means, including a member extending from the cover plate into the chute and a coacting locking member mounted on the interior of said chute wall, whereby said cover plate is locked in 90 place on said housing, a depository into which the chute delivers articles passed therethrough, and means accessible only within the depository, whereby said coacting locking member may be adjusted to release said cover plate for removal from the housing.

100

6. The combination with a deposit chute having a wall, a housing on the exterior of said wall, means mounted in said housing and

extending into the chute permitting articles to pass through the chute in one direction only, a cover plate for the housing, means, including recessed members secured to the cover plate and extending into the chute and locking members mounted on the interior of said chute wall and adapted to engage in the recesses of said recessed members, for locking said cover plate in place on said housing, a depository into which the chute delivers articles passed therethrough, and a releasing 110

115

120

125

130

member disposed within the depository and connected to said locking members, whereby said locking members may be disengaged from said recessed members to release said

5 cover plate for removal from the housing.

This specification signed and witnessed this

12 day of May, 1928.
